DIE LOCKING MECHANISM

Raymond G. Rahe, Brentwood, Pa., assignor to
 Jas. H. Matthews & Company, Pittsburgh, Pa.,
 a corporation of Pennsylvania

Application May 9, 1941, Serial No. 392,720

2 Claims. (Cl. 101—28)

This invention relates to new and useful improvements in die holders, more particularly on the means for locking a plurality of interchangeable marking dies in the holder.

It is among the objects of the invention to improve the locking bolt that operates the locking finger of a die holder such as is disclosed in United States Letters Patent No. 1,503,842, granted August 5, 1924.

The invention will become more apparent from a consideration of the accompanying drawing constituting a part hereof in which like reference characters designate like parts and in which:

Fig. 1 is a view in front elevation of a die holder and marking dies assembled therein;

Fig. 2 a side elevational view partially in cross-section;

Fig. 3 a vertical section of the die holder with the locking mechanism in elevation; and

Fig. 4 a side elevation partially in cross-section of the holder and locking mechanism.

With reference to the several figures of the drawing, the structure therein illustrated comprises a holder 1 shaped to be conveniently gripped by the hand, having a somewhat rounded top end 2 for receiving hammer blows. The bottom central portion of the holder 1 is slotted, as shown at 3, Figs. 3 and 4, the slot extending vertically and being of a width of the dies 4 that are assembled therein. The length of the slot 3 is such as to accommodate a plurality of dies which may be letters or numbers for marking steel products or the like. The holder 1 is provided with a transverse slot 5 about midway of the vertical distance of slot 3 for receiving the end 6 of a spring finger or strap 7 that is secured by a bolt generally designated by the reference numeral 8, the end of the finger 6 being curved as shown at 9.

The structure so far described is disclosed in the prior art patent herein referred to. The novel fastening means of the present invention will now be described. The die holder is provided with a transverse opening 10 having a counterbore 11 at one side and a threaded counterbore 12 on the other side. The bolt 8 extends through an opening in the spring strap 7 and is provided with a shoulder 13 that is movable in the counterbore 11. The shoulder 13 constitutes an abutment for the strap 7 which is held against the shoulder 13 by the nut 14 so that upon axial movement of the bolt 8 in the opening of the holder, the spring strap 7 will be bodily moved in and out of the slot 5.

Disposed within the threaded opening 12 is

5 a coil spring 15 abutting the holder at one end and a collar 16 which is threaded to the bolt 8 at the other end. The coil spring and collar 16 are disposed within a counterbore 17 of a ring nut 18 having an exterior thread engaging the thread 12 of the holder.

The ring nut 18 is counterbored at 19 to be freely slideable around a nut 20 that is secured at one end of the bolt 8. As shown in Fig. 2, 10 the dies 4 are provided with notches 4a to be engaged by the finger 6 of the spring strap 7. The operation of the locking mechanism will now be described.

As shown in Fig. 3 the ring nut 18 has been 15 turned counter-clockwise to release the bolt 8 which by action of the coil spring 15 assumes a neutral position in which position the finger 6 extends into the vertical slot 3 that engages the notches 4a of the dies.

By continuing to turn the ring nut 18 counter-clockwise, the bolt becomes locked, as does the spring finger 6. By turning the ring nut 18 in a clockwise direction, the bolt 8 is displaced as shown in Fig. 4 of the drawing to clear the spring finger 6 from the slot 3 to permit removal of the die.

By means of the positive unlocking and locking mechanism, the spring strap 7 can be moved into and out of engagement with the notches of the dies without the need of springing tools, as heretofore required, thereby eliminating distortion of the spring finger, which would commonly result when the finger was sprung with a tool.

By the positive locking means, the uniform engagement of the spring finger with all of the dies is assured, thereby providing for alignment and locking of the dies in the holder.

Although one embodiment of the invention has been herein illustrated and described, it will be evident to those skilled in the art that various modifications may be made in the details of construction without departing from the principles herein set forth.

I claim:

45 1. In a die holder for removable dies, a spring strap for locking the dies in said holder, a spring bolt on which said strap is mounted, a ring nut having threaded portions interacting with threads on said bolt and holder, said nut having a counterbore and a coil spring disposed therein, whereby upon rotation of the nut to compress the spring the bolt will be initially relieved of spring tension to release the spring strap and upon further movement bodily move the strap out of contact with the dies, and upon

rotation of the nut in the opposite direction move the strap into locking engagement with the dies.

2. In a die holder for removing dies, a vertical slot for receiving a plurality of dies, a transverse slot communicating with said first named slot, a bolt extending through a counterbored opening of said holder, a spring strap mounted on one end of said bolt having a finger disposed in said transverse slot, a ring nut engaging a

10 threaded end of the bolt and a threaded surface of the counterbore in said holder, and a coil spring disposed around said bolt and abutting the end of the counterbore and said ring nut whereby rotation of the nut in one direction will release tension on said strap spring and positively move the finger out of the die slot, and rotation in the opposite direction will positively lock the finger with the dies in the holder.

RAYMOND G. RAHE.
